United States Patent Office

Des. 205,250
Patented July 12, 1966

205,250

JAR

Walter M. Ballard, Whittier, and Gerald W. Neese, Compton, Calif., assignors to Purex Corporation, Ltd., Lakewood, Calif., a corporation of California

Filed Mar. 23, 1965, Ser. No. 84,410

Term of patent 14 years

(Cl. D58—25)

FIG. 1 is a side elevational view of a jar embodying our new design;

FIG. 2 is a top plan view;

FIG. 3 is a bottom plan view;

FIG. 4 is a fragmentary sectional view taken on the line 4—4 of FIG. 1; and

FIG. 5 is a fragmentary sectional view taken on the line 5—5 of FIG. 4.

We claim:

The ornamental design for a jar, substantially as shown.
